UNITED STATES PATENT OFFICE.

FRANK W. MERRICK, OF BOSTON, MASSACHUSETTS.

DEVICE FOR USE IN LASTING.

Application filed March 31, 1926. Serial No. 98,725.

The invention consists in a novel device for use in the process of lasting, designed for holding an upper to a last, with the last, the applied shoe-parts, and the applied device, 5 collectively portable and manually presentable to a machine for applying fastenings. The said device comprises, essentially, portable pad-carrying means, adapted for engagement with a last, and equipped with a 10 pad adapted to hold by pressure the central portion of the fore-part of the upper against the central portion of the fore-part of the last, leaving the upper unobstructed and accessible to the operator along the sides and adjoining 15 the toe of the last and free to be manipulated by him into place, as well as permitting unobstructed application of fastenings around the sides and toe-end of the last.

An important intended use of a device embodying the invention is in lasting upper and sole of a shoe with outturned upper-flange, otherwise known as a stitch-down shoe, and in making application at once of permanent 25 fastenings, preferably stitches in the form of a stitched seam, connecting the outturned upper-flange with the outstanding sole-margin.

The device enables an upper to be localized in proper position upon a last, and permits the upper to be pulled into position beneath 30 the pad in the operation of localizing the upper. In virtue of being so contrived as to leave the marginal portions of the upper free and unobstructed, as well as accessible, it permits the operator to stretch and adjust the 35 skirt of the upper along the sides of the last and around the toe-end of the last, before as well as during the application of fastenings securing the margin of the upper, thereby disposing of any fulness in the said skirt, 40 without change in the location of the upper with relation to the last.

The invention is characterized by various features to which reference is made in the following description and in the claims at 45 the close of this specification.

In the drawings,—

Fig. 1 shows in side elevation a device embodying the invention, in working relation with a last having applied thereto an upper and a sole, certain small portions of the last, 50 upper, and sole being broken away.

Fig. 2 is a plan view thereof, with a small portion of the upper broken away.

Having reference to the drawings,—

55 The last 1, a shoe-upper 2, and a sole 3, are shown in assembled relation, in readiness for

the margin of the upper to be drawn into place and made fast to the sole.

In the case of the illustrated embodiment of the invention, a pad is shown at 4, a carrying lever therefor is shown at 5, a support for the said carrying lever is shown at 6, and at 7 is shown means for actuating said lever and locking it with the pad holding the central portion of the upper pressed against the central portion of the fore-part of the last. Means for mounting the device upon the last is shown at 8.

In this instance, the mounting means 8 is a 70 pin or post which, in making application of my device to a last, is inserted into the usual socket 9, Fig. 1, provided in the heel-part of the last. The said pin or post is adapted to slide lengthwise within the said socket, and to turn therein. It has a hole made transversely through its outstanding portion, and within this hole is received the stem or shank of the support 6.

The support 6 is constituted by a bar, the carrying lever 5 of the clamping foot or pad 4 being mounted pivotally at 51 upon the front end of such bar. The supporting bar 6 is held in fixed relation with respect to pin or post 8, with capacity for adjustment in the direction of its length and that of the last, by 85 means of a clamping screw 10 occupying a screw-threaded hole in the post 8 and adapted to engage by its inner end with the stem or shank of bar 6. A longitudinal flattened surface 61, or it might be a groove, engaged by 90 said end of the screw, provides against turning movement of the bar within the hole, and thereby prevents the pad or foot 4 from lateral displacement such as would be incident to such turning movement relative to the pin 95 or post 8.

The means, 7, for actuating the clamping lever 5 to cause the clamping foot or pad 4 to be pressed upon the upper 2 and fore-part of the last 1, is a cam-lever which is connected pivotally at 71 with clamping lever 5. The cam-portion, 72, of lever 7 acts against the back of bar 6, and is so formed and related that when the handle of lever 7 is swung toward bar 6 the cam-portion 72 is 105 carried in between the pivot 71 and the bar, thereby actuating the lever 5 to bear the clamping foot or pad 4 toward the top of the fore-part of the last. In this position of the cam-lever the reactive stress acts radially, or 110 substantially so, from the pivotal axis at 71 through cam 72 against the back of bar 6,

and hence the cam-portion of the cam-lever acts to lock the clamp in closed condition. The cam-lever constitutes a toggle by means of which the pad-carrying lever may be actuated to cause the pad to hold by pressure the central portion of the fore-part of the wiper against the central portion of the fore-part of the last, said toggle being self-locking to keep the pad in contact with the upper 4. 5 A leaf-spring 11, made fast to the back of carrying lever 5 by the head of the same bolt, 12, that fastens the clamping foot or pad to the underside of such lever, acts with a tendency to move the lever 5 in the direction opposite that in which such lever is moved by means of cam-lever. When the cam-lever is turned around pivot 71 so as to relieve the pressure of cam 72 against the bar 6, the said spring acts to raise clamping foot or 10 pad 4 from the upper and last. 15

The clamping foot or pad 4 is composed of a strip, 41, Fig. 1, of elastic metal, bent into elliptical form and having its ends brought together, overlapped, engaged by 20 bolt 12, and held detachably in place against the underside of the carrying lever 5 by means of the nut 121 applied to the threaded stem of bolt 12. A covering, 42, of leather or other equivalent protecting material, is 25 applied to the strip 41 to prevent injury to the upper 2 when the clamping foot or pad is pressed home against the upper and last.

In practice, the upper 2 being in place around the last, the illustrated device is 30 applied in working relation with a last, the upper having been adjusted into proper position relative to the last, and then the cam-lever 7 is manually operated to actuate the clamping foot or pad 4 to clamp the fore-part 35 of the upper against the top of the fore-part of the last. The device permits the upper to be shifted or adjusted relative to the last and sole, and to be smoothed, as may be 40 found necessary, and will hold the upper in place so effectually as to enable the usual lasting tacks or other fastenings to be dispensed with.

As the action of the cam 72 takes effect in 45 pressing clamping foot or pad 4 against the upper and last, the tendency thereby developed to lift the forward end of arm 6 creates a tendency to tilt post 8 within socket 50 of the last. This latter tendency causes the post to cramp or bind within the socket 55 so as to oppose movement of the post outward of the socket. Such clamping or binding will take effect, whatever the extent of elevation of the post within the socket, and permits the post to be set higher up above 60 the bottom of the socket if required by way of adjustment in case of different sizes of lasts, or for other reasons.

The post 8 is so proportioned in length, so 65 formed, and so related to other parts, that it is capable of being pushed into the socket

9 of the last to an extent slightly in excess of that required to provide for maximum pressure of the pad 4 against the fore-part of the last.

In practice, the upper having been placed 70 around the last, and the post 8 of the clamping device having been inserted into the socket 9 of the last, the post is pushed by the operator inward within the socket until the pad takes sufficient bearing against the central 75 portion of the fore-part of the upper to press such portion lightly against the central portion of the fore-part of the last. This may be done with the cam-lever 7 occupying the relation with respect to arm 6 in which it is 80 shown in Fig. 1, which will be the case when it is intended not to utilize the cam-lever later in producing a secondary or final degree of pressure of the pad. Or, in case it is intended 85 to utilize the cam-lever thus, the pad may be brought to bear suitably for the preliminary pressure after cam-lever 7 has been thrown so as to unlock the pad-carrying lever 90 relative to the supporting arm 6. As the pad takes such bearing, the resistance thereby 95 caused to take effect at the forward extremity of supporting arm 6 operates to tilt the post 8 lengthwise within the socket 9, so that the post cramps or binds within the socket in a manner to hold the post frictionally against movement in the direction of its length, and thereby maintain the pad in contact with the upper so as to hold it lightly against the last. As will be seen in the drawings, the 100 pad, in addition to being located centrally with relation to the fore-parts of the upper and last, is shaped and proportioned so that the upper is left unobstructed and accessible around the pad, along both sides of the last and the toe-end of the last, as illustrated in 105 Fig. 2. Thereby, it is made possible and convenient for the operator, at this stage in the procedure, to take hold of the marginal portions of the upper, at the sides and at the toe, and by pulling in the required directions 110 localize the upper with the required accuracy with respect to the last. If the pressure of the pad has been properly graduated as it 115 should be, the upper may be caused to slip under the pad in one direction or the other, in being adjusted by the operator, until it has been localized to the operator's satisfaction. Thereupon, in case the preliminary pressure has been brought about without 120 operating the lever 7 to unlock the pad-carrying lever 5 and pad, the clamping device is pushed bodily by the operator closer toward the last so as to cause the pad to bear with ample holding pressure upon the upper. As 125 this occurs the post is entered further within the socket, where it remains, held by the frictional gripping, and maintaining the final pressure of the pad upon the upper. Or in case of previous unlocking of the pad-carrying lever 5, the final pressure of the pad is ap-

110

plied through movement imparted by the operator to lever 7, carrying it from unlocking position to its position in Fig. 1, thereby forcing the pad more firmly toward the last. 5 The assembled last, applied shoe parts, and clamp are taken now to the machine for applying fastenings in connection with the upper-margin. These may be fastenings designed to serve primarily the purpose of holding the shoe-parts in lasted relation to each other and the last, but preferably they will consist of the stitches of a permanent seam securing the upper to the sole 3. Such a seam follows the contour of the last. As will be 10 apparent from the drawings, in consequence of the upper being left exposed, accessible, and unobstructed, at both sides of the last and at the toe-end thereof, it may be manipulated freely and conveniently by the operator 15 in smoothing it into place upon and around the last, and the application of fastenings is facilitated. A special advantage in this connection is that the device permits ready manipulation of the upper so as to work into 20 place for being properly fastened in the fulness which forms progressively in stitching along the sides and around the toe of a last. 25 Disengagement of the clamping device from the last and lasted shoe may be effected readily either by throwing cam-lever 7 into its unlocking position, after which post 8 may be withdrawn from socket 9, or with 30 equal facility by swinging arm 6 transversely around the axis of post 8 so as to disengage 35 the pad from the upper by lateral movement of the pad, after which said post may be drawn out of socket 9 as in the other case. In the case of the illustrated construction, this lateral movement of the pad is permitted 40 by rotation of the post within the socket 9, so that the pad turns around an axis within the said socket. 45 As will be apparent, in the broader phases of the invention the construction of a device embodying the principles herein disclosed may vary.

What is claimed as the invention is:—

1. A device for the purpose described, comprising a mounting pin adapted to slide and also to rotate within the socket of the rear part of a last, said pin having a hole which extends transversely through its outer portion, an arm occupying said hole and adjustable therethrough in the direction of the length of the arm to suit the length of shoe operated upon, means combined with the pin and arm to secure the arm in adjusted position, a pressure pad located at the forward end of the arm, and a finger-piece by means of which the said pad may be actuated manually relative to the arm to hold by pressure the central portion of the fore-part of the upper against the fore-part of the last. 55

2. A device for the purposes described comprising an arm having a mounting pin adapted to slide and also to rotate within the socket of the rear part of a last, and to engage frictionally within said socket so as to hold the arm with its pad in contact with the upper, a pad-carrier mounted movably upon 60 said arm, a pad, and an actuating toggle for said pad-carrier to cause the pad to hold by pressure the central portion of the fore-part of the upper against the central portion of the fore-part of the last, said toggle self-locking to keep the pad in contact with the upper. 65

3. A device for the purposes described comprising an arm having means for connecting it detachably with a last, said arm portable with the last, rendering the latter 70 manually presentable to a machine for applying fastenings, a pad-carrier mounted movably upon said arm, a pad, and an actuating toggle for said pad-carrier to cause the pad to hold by pressure the central portion of the fore-part of the upper against the central portion of the fore-part of the last, said 75 toggle self-locking to keep the pad in contact with the upper. 80
